SAFETY MATCH PACKAGE

Joseph I. Schmitt, Houston, Tex.

Application September 10, 1937, Serial No. 163,172

2 Claims. (Cl. 206—29)

The hereinafter described invention relates to matches of the paper variety and more particularly to safety features and advantages in the packaging and use of such matches.

5 Among the objects of the invention is the provision in a match package of a protective cover over the matches contained therein, having a striking surface such that the cover must be closed over the body of matches before a match

10 taken from the package can be struck.

Another object of my invention is to provide a safety match package with a striking surface on the flexible cover portion thereof, and preferably at the end of the cover, so that the match heads

15 in the package will be well covered during the striking operation without the necessity of tucking the cover end into a guide.

20 My invention contemplates among its further objects the automatic covering of the matches in a package of paper matches during the striking of one or more matches as taken from the package before the lighting of same can be effected, thereby preventing practically the premature ignition of the remaining matches of the

25 package.

Another object of my invention is to provide in a paper match package an auxiliary protective covering over the matches contained therein with slack in the material forming said covering so

30 that the matches may be readily withdrawn from the package, in fact, an interior protective covering being provided in addition to the safety striking surface on the main package cover as herein above set out.

35 In order that my invention may be fully understood, reference is made to the accompanying drawing, in which, Fig. 1 shows my improved match package in perspective and in closed position with a portion of the package broken away to show the situation of the striking surface as

40 situated on the outside bottom end of the cover. Fig. 2 is another perspective view showing my improved package as held in the hand and cover lifted for withdrawal of matches. Fig. 3 is an-

45 other perspective view with the hand in the same position as in Fig. 2 and the cover of the package in position during the striking of a match. Fig. 4 is still another perspective view of my invention by which the auxiliary inside protective covering

50 over the matches is shown.

In the illustrative embodiments of my invention, numeral 10 denotes the paper material housing the matches, 11, the material 10 being brought around a sufficient distance, as at 10a, to sub-

55 stantially entirely enclose the match striking

surface 12, when the package is closed as shown in Fig. 1. Match striking surface 12 is preferably situated at the end of the cover portion 10b of housing material 10. Numeral 13 denotes an inside auxiliary paper protective covering secured at its opposite ends to the material of housing 10, being made with surplus of paper of a relatively thin character as compared to the paper housing material 10, so as to permit ready removal of a match from the side of the package 10 when cover 10b is lifted as shown in Fig. 4.

The new utility of my improved safety match package is well brought out in Fig. 3, which shows how the cover 10b is held down over the matches 11, between the thumb and forefinger 15 during the striking of a match against the surface 12, in protection of the user.

In the handling of my improved safety match package, the cover 10b carrying striking surface 12 resides against the relatively stiffer and thicker bottom portion of the package, as provided by the lower ends of the matches where they are secured to the housing 10 by binder 14. This makes a base for the striking surface 12.

The flexibility of the cover portion 10b is such 25 that it requires a comparatively firm base for the striking of a match. This prompts the expression which I choose to state as, automatically covering the matches during the striking thereof, and it will be obvious that the flexible cover can 30 be moved well up or beyond the bottom portion of the package, as held by binder 14, and still the thumb and forefinger would hold the cover 10b over the tips of the matches during striking against surface 12.

35 With the present paper match package, the user is instructed to "close cover before striking"; however, I have found that these instructions are rarely, if ever, observed, in view of the fact that it requires a distinct operation upon the part of the 40 user to effect the protection proposed. With my improved package I eliminate this extra operation, while affording protection to the user by virtue of the cover 10b, as carrying striking surface 12, residing over the matches of the package 45 during the striking operation.

What I claim is:

1. In a book match structure, the combination of a group of matches having a joining base, a cover having one end folded around the said base 50 and forming a front tuck flap thereat, said cover having a portion disposed at the back of the matches and being folded around the match heads, there being another portion of the cover disposed over the front of the matches and form- 55

ing a cover flap, the outer face of the cover flap at the extreme end margin thereof having a transverse band of match igniting material thereon and the tuck flap being of such length that the band of igniting material is fully concealed and protected by the tuck flap when the end margin of the cover flap is tucked in under the tuck flap in the normal closed position of the cover flap and the tuck flap may be used as a backing for the band of igniting material while a match is being struck.

5. 2. In a book match structure, the combination of a group of matches having a joining base, a cover having one end folded around said base and forming a front tuck flap thereat, said cover having a portion disposed at the back of the

matches and being folded around the match heads, there being another portion of the cover disposed over the front of the matches and forming a cover flap, the outer face of the cover flap adjacent the end margin thereof having a transverse band of match igniting material thereon and the tuck flap being of such length that the band of igniting material is substantially entirely concealed and protected by the tuck flap when the end margin of the cover flap is tucked in under the tuck flap in the normal closed position of the cover flap and the tuck flap may be used as a backing for the band of igniting material while a match is being struck.
